SHEET REGISTERING DEVICE FOR PRINTING PRESSES

Lawrence R. Johnson, Cleveland, Ohio, assignor to The Chandler & Price Company, Cleveland, Ohio, a corporation of Ohio

Application May 2, 1936, Serial No. 77,536

7 Claims. (Cl. 101—414)

This invention relates, as indicated, to sheet registering devices for printing presses.

A primary object of the invention is to provide an improved sheet receiving member for such a device which is adapted to register a wide range of paper stocks, without necessitating the adjustment of the elements of the member for each grade or weight of paper.

Another object of the invention is to provide a member of the character described, which will occupy as little of the effective area of the platen as possible, and which is of minimum height.

A further object of the invention is to provide a member of the character described, having elements, which, although small in size, will function effectively to register sheets without cramping or pinching of the sheet between such elements.

A further object of the invention is to provide a member of the character described, which can be inexpensively manufactured but which is sufficiently rugged to withstand continued usage.

To the accomplishment of the foregoing and related ends, said invention, then, consists of the means hereinafter fully described and particularly pointed out in the claims; the annexed drawing and the following description setting forth in detail certain devices embodying the invention, such disclosed means constituting, however, but a few of the various mechanical forms in which the principle of the invention may be utilized.

In said annexed drawing:

Fig. 1 is a perspective view of one form of the sheet-receiving member; Fig. 2 is a front elevation of the member shown in Fig. 1, showing a sheet engaged thereby; Fig. 3 is a top plan view of said member; Fig. 4 is a longitudinal cross-sectional view on line 4—4 of Fig. 3; Fig. 5 is a cross-sectional view on line 5—5 of Fig. 3; Fig. 6 is a top plan view of a modified form of sheet-receiving member; Fig. 7 is a longitudinal cross-sectional view on line 7—7 of Fig. 6; Fig. 8 is a transverse cross-sectional view on line 8—8 of Fig. 6; Fig. 9 is a top plan view of another modified form of sheet-receiving member; Fig. 10 is a longitudinal cross-sectional view on line 10—10 of Fig. 9; Fig. 11 is a top plan view of still another modified form of sheet receiving member, and Fig. 12 is a fragmentary longitudinal cross-sectional view on line 12—12 of Fig. 11.

Referring to Figs. 1 to 5 of the drawing, there is disclosed a sheet-receiving member having the usual shank 1 in the form of a metal strip pro-

vided with the usual slot 2 in its rear end and with laterally spaced tines 3 at its front end. Each of these tines, as will be noted in Figs. 2 and 4, is beveled or smoothly rounded at its side edges and also at its front end, so as to facilitate sliding of the paper sheets onto the tines and at the same time obviate any possibility of such sheets becoming scratched or otherwise marred.

Secured to the upper surface of the shank 1 of the sheet receiving member, as by rivets 4, is a sheet engaging element 5 which extends centrally of the shank and is designed to cooperate with the tines 3 to grip a sheet of paper for registering purposes. The element 5 is made from a single length of relatively small gauge round spring wire and consists of a curved stop 6 at its rear end, a shank portion 7 which lies closely adjacent the shank 1 and extends through the rivets 4, a shoulder 8, an offset portion 9 parallel with the shank 1 and a curved finger 10 which terminates at its front end in a closed circular loop 11. The curved finger 10 extends downwardly into the space between the tines 3 and the loop 11 is disposed directly above the space between the front ends of the tines, the loop lying in an inclined plane.

The curved stop 6 and the shoulder 8 of the element 5 cooperate with the rivets which they respectively engage to lock the element in position, and the flat bearing of the stop 6 on the shank serves to prevent axial rotation of the wire element 5.

The construction and arrangement of the tines 3 and cooperating element 5 is such that a sheet of paper S presented to the member will easily ride up over the tines and be engaged between these tines and the curved finger 10, in the manner clearly shown in Fig. 2, the sheet being slightly bent or curved to an extent sufficient to insure against displacement from the member during the registering movement. The sharp upward inclinaion of the loop 11 will insure proper reception of the sheet by the member, and the smooth surfaces of this loop and the curved finger 10 will insure against scratching or marring of the sheet during such reception as well as during the registering movement. It will be further noted that ample spaces are provided between the wire finger 10 and the inner edges of the tines 3, so that the sheet, when received by the member, will not be bent or crimped to an excessive degree, as when employing registering devices embodying flat spring clips or fingers. Furthermore, chattering of the sheet which takes place when a sheet-receiving member which

bends or crimps the sheet to too great an extent slips off the sheet, is avoided by the employment of a wire finger, as embodied in the present device.

5 The use of a wire finger is further advantageous in that it permits the width of the sheet-receiving member to be reduced to a minimum, as shown in the drawing. Due to this reduced width, the member will occupy but a small portion 10 of the effective area of the platen and a relatively small movement of the member will swing it clear of the sheet, so that printed matter close to the edge of the sheet will not be injured. In this connection it will be noted that the tines 15 3 are confined within a space no wider than the width of the shank 1 of the sheet-receiving member, but it will be apparent that the use of the wire finger will permit the distance between the tines 3 to be reduced to an extent even greater 20 than that shown, so that the tines will be confined within a space less than the width of the shank 1.

Due to the high degree of resiliency of the 25 spring finger, such finger does not need to be adjusted for different stocks, and such parts as screws, thumb-nuts, blocks, etc., which are found in other devices, are not required, except in rare cases, where the work of the printer varies from 30 very thin paper to very thick board, in which event, an adjusting element, as shown in Figs. 6, 7, and 8 may be used. The construction of the device, moreover, is such that the overall height of the device may be easily confined within the 35 allowable limit of .140" which is permitted for devices of this character, as employed in platen presses.

The use of a wire element further permits the initial cost of the sheet-receiving member and the cost of replacements to be reduced to a minimum, as wire is relatively inexpensive, and in the 40 event of injury to the wire element, it can be quickly and easily removed and replaced.

In that form of the invention shown in Figs. 45 6 to 8, the wire element 5 has an inherent upward tension and means are provided for adjusting the height of the finger 10. Such means consists of a screw 12 which is riveted to the shank 1 and is longitudinally slotted as at 13 to provide a passage for the shank 7 of the wire element 5, and an adjusting nut 14, whereby the height of 50 the finger 10 of said wire element may be varied to accommodate different thicknesses of paper stock.

In that form of the invention shown in Figs. 9 55 and 10, the wire element 5 is permanently secured to the shank 1, as by spot welding the wire to said shank at spaced points 15.

In that form of the invention shown in Figs. 11 60 and 12, the tines 3 are joined at their forward ends, the upper surface of the connection 16 being transversely curved in the same manner as the tines. By thus connecting the forward por-

tions of the tines, the possibility of a sheet entering below one of the tines and above the other is avoided.

Other modes of applying the principle of my invention may be employed instead of the one 5 explained, change being made as regards the structure herein disclosed, provided the means stated by any of the following claims or the equivalent of such stated means be employed.

I therefore particularly point out and distinctly 10 claim as my invention:—

1. A sheet-receiving member having a pair of laterally spaced longitudinally-extending tines, and an element cooperating with said tines to grip a sheet of paper, said element being formed 15 from wire and having a portion in the form of a curved finger extending downwardly into the space between said tines.

2. A sheet-receiving member comprising a lower member having longitudinally extending 20 transversely spaced, sheet-engaging portions, and means connecting the forward ends of said sheet-engaging portions.

3. A sheet-receiving member comprising a lower member having longitudinally extending trans- 25 versely spaced sheet-engaging portions and a wire element cooperating with said sheet-engag- ing portions to grip a sheet of paper.

4. A sheet-receiving member comprising an ele- 30 ment having longitudinally extending trans- versely spaced sheet-engaging portions and an element cooperating therewith to grip a sheet of paper, said last-named element being formed from wire and having a forward portion in the form of a curved finger terminating at its front 35 end in a loop.

5. A sheet-receiving member comprising an ele- 40 ment having longitudinally extending trans- versely spaced sheet-engaging portions and an element cooperating therewith to grip a sheet of paper, said last-named element being formed from wire and having a forward portion in the form of a curved finger extending into the space 45 between said transversely spaced sheet-engaging portions and terminating at its front end in a loop disposed adjacent the front ends of said sheet-engaging portions.

6. A sheet-receiving member comprising a lower member having longitudinally extending transversely spaced sheet-engaging portions, and 50 means connecting the forward ends of said sheet-engaging portions, said means having a trans- versely curved upper surface.

7. A sheet-receiving device comprising a lower member having a shank, longitudinally extend- 55 ing transversely spaced sheet-engaging portions extending from the forward end of said shank and lying within the confines of the edges of said shank, and an element cooperating with said sheet-engaging portions to grip a sheet of paper. 60

LAWRENCE R. JOHNSON.
